COFFEE-CHAFF EXTRACTOR.

957,130.

Specification of Letters Patent. Patented May 3, 1910.

Application filed April 6, 1909. Serial No. 488,724.

To all whom it may concern:

Be it known that I, EDGAR T. WEAR, citizen of the United States, residing at Oakland, in the county of Alameda and State of California, have invented certain new and useful Improvements in Coffee-Chaff Extractors, of which the following is a specification, reference being had therein to the accompanying drawing.

10 This invention relates to separators for grinding machines and has particularly in view a device of the character specified in which chaff and other light foreign material may be separated from the ground material 15 and conveyed to a receptacle.

In carrying out the generally stated object of the invention it is contemplated employing a suction device which may be operated by the grinding machine and provided with a suction pipe having one end provided with a hopper through which the ground material passes from the grinding machine so that the force of the suction device is exerted directly thereon to separate 25 the foreign material therefrom and convey the same through said pipe and a discharge pipe to a screening device in which the air is broken into particles to permit the same to escape and allow the separated foreign 30 material to fall into a glass receptacle.

In connection with the foregoing, the invention also contemplates employing suitable draft regulating devices for controlling the force of the suction, and also suitable 35 cut-off devices whereby the separator may be cut-off from operating upon the material being delivered from the grinding machine.

It will be understood, of course, that the essential features of the invention necessary 40 in the practical application of the separator are susceptible of a wide range of details and structural arrangements, but one preferred and practical embodiment of the same is shown in the accompanying drawings, 45 wherein—

Figure 1 is a view in side elevation of the improved separator showing the same attached to a coffee mill, the latter being indicated by dotted or broken lines. Fig. 2 is a 50 top plan view of the separator. Fig. 3 is a top plan view of the receptacle into which the separated material is delivered, showing the manner of connecting the same with the grinding mill and also showing an air-deflecting screen mounted therein. Fig. 4 is

a fragmentary vertical sectional view thereof. Fig. 5 is a view in front elevation of the suction device showing its operating gears, parts of said figure being broken away. Fig. 6 is a detail elevation of the hopper carried by the suction pipe. Fig. 7 is a broken vertical sectional view of the same. Figs. 8 and 9 are detail horizontal and vertical sectional views of the suction pipe showing a draft regulator carried thereby.

Referring to the accompanying drawings by numerals 1 designates a suction pipe, one end of which is in communication with a suction device 2 which may be a fan which is operated by a gear 3 held in mesh with a large gear 4 which in turn is operated by a small gear 5 mounted upon a motor shaft 6. The large gear 4 and small gear 5 are enclosed in a housing or gear casing 7, and the gear 3 is housed in an outstanding casing 8 projecting from the fan casing 9. Said fan casing may be supported by a bracket 10 carried by the base of a grinding machine. The said suction pipe 1 has its inlet end provided with a pipe coupling 11 which engages with a tube extension 12 of an open hopper 13 which is held in engagement over a discharge outlet of a grinding machine by means of a set screw or equivalent detachable fastener 14. Said hopper 13 is provided with an upstanding lip 15 which prevents the material from the grinding machine being spilled, as will be obvious.

The suction pipe 1 at its inlet end portion may be in the form of an elbow and is provided with a slide valve 16, and intermediate said slide valve and the suction device, it is provided with an opening 17 which may be covered or uncovered by means of a rotatable sleeve 18 surrounding said pipe and provided with an opening 19 which when brought into alignment with the opening 17 admits more air to said pipe, and thus acts as a draft regulator, as will be obvious. The slide valve 16 serves to cut-off the force of the suction device from the hopper 13, so that when material is being pulverized by the grinding machine, the same will not be acted upon by said suction.

The pipe 1 enters the central portion of the fan casing 9 and delivers the material therein where it is acted upon by the force of said fan and forced out through a discharge pipe 20 and into a hopper-shaped fine mesh screen 21 fitted over the circular

open end of a glass receptacle 22. Said receptacle 22 has a circular screen 23 suspended therein by means of holding clips 24. The screen 23 is provided with a plurality of semi-spherical lugs 25 which are scattered about its upper surface and serve to divide the air current and thereby break its force and also to deflect the said air to and through the hopper-shaped screen 21 to prevent the same passing into the receptacle and thus agitate the material therein.

The receptacle 22 may be held in engagement with the base of the grinding machine by means of the holding clips 26 which are formed of spring metal and embrace its base, as is clearly shown in Figs. 1 and 3.

The operation of the separator is as follows.—The suction fan being operated by the motor through the described gearing, a strong suction will be created in the pipe 1 which acts upon the material falling from the discharge outlet of the grinding machine into the hopper of the said pipe, thereby separating the light foreign particles therefrom and conveying the same through said pipe and into the hopper-shaped screen 21, the mesh of which is fine enough to prevent any of the material escaping therefrom, but permits considerable of the air to escape. From the hopper-shaped screen, the material falls upon the screen 23 and falls through the same and into the receptacle 22, the air which has not escaped through the hopper-shaped screen being deflected by the lugs of said screen 23, as has been previously explained.

As has been stated before, the receptacle is of glass so that the contents thereof may be visible to permit the attendant to see when it is necessary to empty the same and also to inspect the contents.

It will be seen from the foregoing that the described separator may be readily applied to the discharge end of a grinding machine so that its force of suction may be applied directly to the material being discharged, and thus effectively separate the foreign material therefrom. And it will also be seen that through the interposed cut-off valve in the suction pipe, the separator may be prevented from acting on the material being discharged, so that when material is being pulverized it will not be drawn through the suction pipe, and through the medium of the described draft regulator the force of suction may be increased or diminished.

What I claim as my invention is:—

1. A device of the character described comprising a suction pipe adapted for detachable connection with an outlet of a grinding machine, a discharge pipe receiving the material from the suction pipe, a hopper-shaped screen into which said discharge pipe delivers and which permits the

air to escape, a receptacle in communication with said screen, and a screen carried by said receptacle and provided with air-deflecting means.

2. A device of the character described comprising a suction pipe adapted for detachable connection with an outlet of a grinding machine, a discharge pipe communicating with said suction pipe, a screen into which said discharge pipe delivers, a receptacle in communication with said screen, and a screen mounted in said receptacle and provided with air deflectors.

3. A device of the character described comprising a suction pipe adapted for detachable engagement with an outlet of a grinding machine, means for creating a suction in said pipe, a discharge pipe in communication with the suction pipe, a screen connected to said discharge pipe which permits escape of air, a receptacle also connected with said screen, and a second screen carried by said receptacle and provided with air deflectors.

4. A device of the character described comprising a suction pipe adapted for connection with a discharge outlet of a grinding machine, means for creating a suction therein, a discharge pipe in communication with the suction pipe, a hopper-shaped screen having one end connected with said discharge pipe, a receptacle having its upper end surrounded by said hopper-shaped screen, and a screen suspended within said receptacle and provided with air deflectors.

5. A device of the character described comprising a suction pipe, adapted for engagement with an outlet of a grinding machine, means for creating a suction therein, a discharge pipe in communication with the suction pipe, a receptacle, a screening connection between said discharge pipe and said receptacle, and a second screen suspended within said receptacle.

6. A device of the character described comprising a suction pipe adapted for engagement with an outlet of a grinding machine, means for creating a suction therein, a discharge pipe in communication with the suction pipe, a receptacle, a screening connection between said discharge pipe and said receptacle, and a second screen suspended within said receptacle and provided with a plurality of air deflectors.

7. A device of the character described comprising a suction pipe adapted for engagement with an outlet of a grinding machine, means for creating a suction therein, a discharge pipe in communication with the suction pipe, a receptacle, a screening connection between said receptacle and said discharge pipe for permitting air to escape, and a second screen suspended within said receptacle and provided with a plurality of lugs for deflecting air from said receptacle.

8. A device of the character described comprising a suction pipe adapted for engagement with an outlet of a grinding machine, means for creating a suction therein, 5 a discharge pipe in communication with the suction pipe, a screen carried by said discharge pipe and being of a hopper shape, a receptacle connected with said screen, and

an air deflecting screen carried by said receptacle.

In testimony whereof I hereunto affix my signature in presence of two witnesses.

EDGAR T. WEAR.
